UNITED STATES PATENT OFFICE.

WARREN C. JOHNSON, OF OSKALOOSA, IOWA.

COAL-DRILL.

SPECIFICATION forming part of Letters Patent No. 391,157, dated October 16, 1888.

Application filed March 30, 1888. Serial No. 268,985. (No model.)

To all whom it may concern:

Be it known that I, WARREN C. JOHNSON, of Oskaloosa, in the county of Mahaska and State of Iowa, have invented a new and useful Improvement in Coal-Drills, of which the following is a specification, reference being had to the annexed drawings, forming a part thereof, in which—

Figure 1 is a side elevation of my improved coal-drill. Fig. 2 is a front elevation of the drill-frame with the drill proper removed; and Fig. 3 is a horizontal section taken on line *x x* in Fig. 2.

Similar letters of reference indicate corresponding parts in all the views.

The object of my invention is to provide a coal-mining drill which may be clamped at any desired elevation by tightening a bolt.

My invention consists in the combination, with the sliding pieces of a coal-drill, of a sleeve interposed between the sliding supports of the drilling apparatus and a bolt passing through the said sliding supports and through the sleeve and adapted to clamp the sliding supports against the side bars of the frame of the drill, all as hereinafter more fully described.

The frame *A* of the drill is formed of the side bars, *a*, clamped at the top to a distance-piece, *b*, carrying a retaining-point, *c*, and at the bottom to a similar distance-piece, *b'*, carrying an adjustable retaining-point, *c'*. Upon the side bars, *a*, are loosely placed the sliding supports *B* of the trunnions *d* of the coal-drill *C*.

Between the sliding supports *B* is placed a

sleeve, *e*, and in holes formed in the sliding supports *B* is inserted a bolt, *f*, which also passes through the sleeve *e*. The head of the bolt reaches over one of the vertical bars *a*, while the wing-nut *g*, received on the bolt, reaches over the other vertical bar, so that when the nut *g* is turned the vertical bars *a* will be clamped against the inner surfaces of the supports *B*, the said supports being in turn clamped upon the ends of the sleeve *e*. 45

The drill *C* is of the usual construction, and will therefore need no special description.

Having thus described my invention, I claim as new and desire to secure by Letters Patent—

1. The combination, with the side bars, *a*, and sliding supports *B*, of the sleeve *e*, interposed between the sliding supports, and the bolt *f*, passing through the sliding supports *B* and the sleeve *e*, and provided with a head and nut extending over the bars *a a*, substantially as specified. 55

2. A coal-drill formed of the side bars, *a*, and their supports, the drill *C*, provided with trunnions *d*, the sliding supports *B*, fitted to the bars *a* and adapted to support the trunnions *d*, the sleeve *e*, and the bolt *f*, passing through the sliding supports *B* and sleeve *e* and adapted to clamp the bars *a*, sliding supports *B*, and sleeve *e* together, substantially as specified. 60

WARREN C. JOHNSON.
